Atty's.

UNITED STATES PATENT OFFICE

AUGUST D. ZEECK, OF NEW HAVEN, CONNECTICUT, ASSIGNOR TO THE GREIST MANUFACTURING COMPANY, A CORPORATION OF CONNECTICUT

SEWING-MACHINE RUFFLER

Application filed June 27, 1928. Serial No. 288,595.

This invention relates to that class of sewing machine rufflers comprising a reciprocating ruffling blade connected with a pendulous lever which, in turn, is connected with the main lever operated from the needlebar of a sewing machine, the present invention relating to means whereby the throw of the ruffling blade may be varied by a simple adjustment. In accordance with the present invention the pendulous lever is provided with a laterally extending contact lug adapted to be engaged by a regulating lever mounted on the operating lever, the position of said regulating lever being varied to regulate the throw of the ruffling blade, by means of an eccentric pivotally mounted on the fulcrum pin of the main and pendulous levers. The said main lever is provided with a graduated scale, and, extending from the eccentric, is an index finger the tip of which is adjacent to the said scale so that the extent of throw of the ruffling blade may be readily determined by said scale and index finger. In the drawing Figs. 1 and 2 are opposite side views of the improved ruffler. Fig. 3 is a view similar to Fig. 2 but with the parts in different positions, and Fig. 4 is a plan view of the improved ruffler. Referring to the drawing, 12 denotes the frame of the ruffler which is provided with a presser-foot portion 13 adapted for attachment to the presser-bar of a sewing machine. Mounted on a pivot pin 12^a, near the top of the frame 12, are the main and pendulous levers 14 and 15, respectively. Jointed to the lower end of the pendulous lever 15 is a carrier 16 to which is attached the ruffling blade 17. Mounted on the operating lever 14 is a regulating lever 17 having a contact part 17^a (see Fig. 3) and a tail piece 17^b. The part 17^a is arranged to come in contact with a laterally extending lug 15^a on the pendulous lever 15. This contact of the parts 17^a and 15^a occurs when the needle bar of the sewing machine is rising and the ruffling blade is to be forced forward for the ruffling operation; while on the downward stroke of the needle-bar, when

the ruffling blade is to be retracted, the tail piece 17^b of the lever 17 comes in contact with the upper forward edge of a reinforcement 15^b of the lug 15^a.

In the normal adjustment of the parts 55 there will be considerable lost motion between the levers 14 and 15, and this lost motion may be varied, to adjust the throw of the ruffling blade, by means of an eccentric 18 mounted on the pivot pin 12^a 60 and provided with a radially extending index finger 18^a the turned-over tip of which is adjacent to a scale 19 near the curved upper edge of the operating lever 14.

It will be noted that the contact part 17^a 65 of the lever 17 is rather broad, and that the laterally extending reinforced lug 15^a of the pendulous lever, against which the said contact part 17^a is to impinge, at times, is also rather broad, so that when the ruffling 70 blade is to be forced forward for a ruffling stroke, (see Fig. 1) and when most power is required, these broad contact parts will afford sufficient strength so that objectionable wear will be avoided. When the ruff- 75 fling blade is to be retracted and little power is required, the tail piece 17^b of the adjusting lever 17 will come in contact with the upper edge of the reinforcement 15^b of the lug 15^a. (See Fig. 3.)

When the eccentric 18 is adjusted to a position in which the index finger movable therewith points to 0 on the scale 19 there will be so much lost motion between the main and pendulous levers that no movement will be imparted to the ruffling blade which is thus thrown out of operation, as is desirable when plain sewing is to be done. In other words, this simple adjustment will render the ruffling blade neutral or inoperative.

The regulating lever 17 is retained in any desired position of adjustment by a spring washer 20, and the adjusting eccentric is similarly retained in any desired position 85 by means of a friction washer 21.

The ruffler is provided with the usual separator plate 22 fixed to the holder 23 removably mounted on the frame 12 in a well known manner.

From the foregoing it will be apparent that the invention provides a simple and efficient construction whereby the throw of the reciprocating ruffling blade may be conveniently varied as to impart to the said ruffling blade any desired length of stroke, or may be rendered neutral, as will be plainly indicated by the scale 19 on the operating lever 14 and the index finger 18^a extending from the adjusting eccentric 18.

Having thus described my invention, I claim and desire to secure by Letters Patent:—

In a sewing machine ruffler, the combination with a ruffling blade and its carrier, of a pendulous lever having a jointed connection with said carrier and provided with a laterally extending contact lug, an operating lever adapted to be actuated from the needle-bar of a sewing machine, a regulating lever mounted on the said operating lever and having a broad contact part and a tail portion for alternate engagement with said lug, and an adjustable eccentric by which the position of the said regulating lever may be varied to regulate the throw of the said ruffling blade.

In testimony whereof I affix my signature.

AUGUST D. ZEECK.
